APPARATUS FOR SEMIFLUID AND FLUID
EVACUATION

Timothy F. Callahan, Quincy, Mass.

Application July 30, 1930, Serial No. 471,853

4 Claims. (Cl. 214—1)

This invention relates to improved apparatus for semi-fluid and fluid evacuation. More particularly it relates to a method and means for removing from a container or excavation any sand 5 or gravel, or fragmentary or comminuted solid matter which may be immersed or disseminated in a fluid. For example, the invention provides, among other things for removal of sludge from sewage catch basins; pulp and oak bark from 10 vats or other containers; and has a particular utility for evacuation of quick-sand in construction undertakings which may involve excavating in quick-sand areas.

Hitherto it has been difficult indeed to accomplish 15 any sort of excavation at or near quick-sand areas. The liquid or semi-liquid nature of quick-sand causes it to flow into any excavation attempted to be dug in the vicinity. It has been a real engineering problem, requiring the attention 20 and supervision of experts in that particular kind of work, to stem the flow of quick-sand, and to eliminate incident accumulations of water, to an extent which will permit the desired excavation to be made and suitably sheathed, and 25 the necessary masonry installed. Ordinarily the water must be pumped out of a preliminarily prepared area, and must be maintained at a sufficiently low level in the excavation to permit the work to proceed. Great expense has been involved, and always there is the danger of quick- 30 sand flow to an extent which affects the foundations of buildings, roads, etc., in the vicinity. According to the present methods there is a continual pumping out of water until such time 35 as the particular section being worked has been suitably excavated, sheathed and the required masonry installed; and all of this time there is a continual flow of water and quick-sand into the excavation from surrounding areas.

40 In my United States Letters Patent No. 1,326,321, granted December 30, 1919, I have disclosed means designed more particularly for sludge removal, but which is capable of use for excavating in quick-sand. But the theory upon 45 which my said patented device operated is conducive to wear in the case of quick-sand removal. It involves a suction loading, and requires relatively high air pressure to empty, forcing the 50 material through a tube to a place of discharge at the surface. The friction incident to passage of quick-sand through the tube may destroy the tube after a relatively short term of service. And then again, if the material be coarse and heavy, 55 as quick-sand, it may pack and clog the tube

and may interfere with a proper operation of valve or valves.

The present invention provides improved means adapted for handling quick-sand, and numerous other materials which may be immersed or disseminated in liquid, as well as sludge.

It is an object of the invention to provide for evacuation of quick-sand, and various kinds of fragmentary or comminuted solid matter, with a fluid vehicle, by flowing the material, as a semi-fluid, into a fluid-tight receptacle, and discharging it, when said receptacle is elevated, through the same passage by which it entered. A feature resides in the fact that a large quantity of fluid in a container or an excavation is no hindrance 10 to the work of removing solid matter therefrom, but, rather, the fluid is made to play an important part in effecting the evacuation. Another feature resides in the provision for discharge from the pick-up receptacle by gravity outflow through 15 a short, large-diameter passage, thereby ensuring against clogging of the passage, and minimizing wear. A further object is to provide means whereby heavy and solidly packed material to be evacuated, preliminarily may be agitated and 20 converted into a semi-fluid state capable of flowing into the pick-up receptacle. It is moreover, 25 an important feature that means associated with the pick-up receptacle can effectively hold contents against outflow as the receptacle is being 30 elevated, and can release said contents at the will of an operator.

These objects and results may be attained 35 with apparatus including a fluid-tight receptacle and means for lowering and raising the receptacle into and out of the container or excavation from which material is to be evacuated. Conveniently the receptacle may be suspended, on a suitable hoist which may be carried on a truck or other vehicle. The receptacle has a mouth 40 at a bottom location adapted to become embedded in the material as the receptacle is lowered; and a conduit leads from the receptacle to a control point, which may be at the vehicle, with means whereby the interior of the tank may be 45 closed or opened to atmosphere at will, and whereby it may be connected to a source of vacuum which conveniently may be a vacuum tank on the vehicle. Preferably a second tank, containing air under pressure, is carried on the vehicle, with conduit leading into the receptacle 50 and well down toward the latter's bottom, with means for closing said latter conduit and for opening it when desired to inject air pressure 55 into contents of the receptacle.

A second conduit leading from the pressure tank may have a rigid end portion capable of being forced into the material to be evacuated to inject air pressure into the material to preliminarily convert it to a semi-fluid state. The receptacle then may be lowered until the mouth thereof becomes embedded in the material, the vacuum conduit meanwhile being closed both to atmosphere and to the vacuum tank. If the receptacle is immersed in liquid, the mere opening of the vacuum conduit to atmosphere results in flow of material in its fluid vehicle into the receptacle due to the unbalanced heads of water within and outside the receptacle. A sufficient fluid column will cause the receptacle to become substantially filled, and the major portion of the contents will be solid material carried in by the fluid. Should the fluid column be insufficient to fill or nearly fill the receptacle, or if there is too little fluid to move material into the receptacle, suction may be employed to draw the material in.

The fluid which enters the receptacle may be employed to seal the mouth in conjunction with the closing of the receptacle to atmosphere. Such a seal is effective to hold the contents while the receptacle is elevated and positioned for discharge. Then, by opening the receptacle to atmosphere, the seal is destroyed and contents can flow out by gravity. Or, if the contents are too solidly packed to flow, a blast of air may be injected therein through the pressure conduit thereby to agitate the material sufficiently to permit of its falling out of the receptacle by gravity.

For cases having little fluid, such as for sludge removal from sewerage catch basins, a two way flap type of valve may serve in place of the water in providing a seal. In such a case suction may be employed for filling the receptacle, and air pressure, if necessary, may force contents out at the place of delivery.

It is intended that the patent shall cover, by suitable expression in the appended claims, whatever features of patentable novelty exist in the invention disclosed.

In the accompanying drawings:

Figure 1 is a diagrammatic view of an assembly which may be employed for practicing the invention for evacuation of various kinds of material, including quicksand and sludge.

Figure 2 is a diagrammatic view of an assembly which is particularly adapted for use where a large head of fluid is available for moving the material into the receptacle;

Figure 3 is a diagrammatic view of an assembly which is particularly adapted for handling sludge and the like;

Figure 4 is an elevation, in medial section, of one form of my improved pick-up receptacle;

Figure 5 is a view similar to Figure 4 only showing a modified form; and

Figure 6 is an elevation, in medial section, of a receptacle particularly adapted for sludge removal, and having a valve serving the purpose of water for effecting a seal.

In the practice of my invention I prefer to employ a vehicle 10 on which may be rotatably mounted a suitable hoist 12 for suspension of my improved pick-up receptacle 14, by means of a cable or the like 16. In the diagrammatic showing of Figure 1, the vehicle 10 carries also a compressed air tank 18, and a vacuum tank 20, with suitable motor 22 and generating means 24, which

latter is adapted both to generate pressure in tank 18 and to create a vacuum in tank 20.

As a preliminary step to the removal of any solid matter, which may have become packed solidly under a body of fluid, I prefer to agitate the material and thus to convert it into a semi-fluid state capable of being flowed with its fluid vehicle into the receptacle 14. For this purpose I provide a pressure conduit 23 leading from the tank 18, with suitable control valve 25. The conduit has at its end a pipe 26 which may be forced down into the material a considerable distance, as seen in Figure 1. Then, by opening valve 25, a blast of air may be driven into the massed material, causing its dispersal in the fluid, whereby it more readily may be moved in the act of evacuation.

For quick-sand removal, or for removal of other solid matter having a considerable column of water or other fluid above it, the fluid, in conjunction with atmospheric pressure is utilized as the motivating force for moving material into my pick-up receptacle. To this end I provide a conduit 28 leading from the interior of the receptacle to a control point, which may be at the vehicle 10, where a valve 30 may be opened or closed to open or to close the receptacle 14 to atmosphere at the will of the operator. And, preferably, the valve 30 will be an ordinary three way valve, and the conduit 28 will be continued on to the vacuum tank 20, so that the conduit may serve as a vacuum tube for suction loading of the receptacle under some conditions. Thus, as represented in Figure 1, the valve 30 may be set to close the receptacle to atmosphere, or to open it to atmosphere; and, in still another position, may open the receptacle to suction from the vacuum tank 20.

In Figure 4 the receptacle 14 is shown in detail. It has in its bottom an inlet and discharge pipe 15 which is fairly large in diameter, and which extends a little below the bottom of the receptacle. In the opposite direction it extends into the interior of the receptacle where a hood 17 is arranged, in spaced relation, over its mouth, for a purpose later to be described.

In cases where a large head of fluid is available, as in the excavation of Figure 1, the receptacle 14 may be lowered into the fluid while valve 30 is set to close its interior to atmosphere, and ordinarily will descend of its own weight sufficient to embed the end of pipe 15 in the material which, preliminarily, may have been agitated as above described. However, if its weight be insufficient in any case, weights 19 may be added as needed. Air entrapped in the receptacle ordinarily will prevent water from entering it to any substantial extent, during its descent but, if too much enters under particular conditions, compressed air may be injected through conduit 21, to force the water out before it reaches the material, or to hold back the water during the descent of the receptacle.

Once the pipe 15 has its end embedded in the material, the receptacle becomes completely sealed. Then, by setting valve 30 to open the interior of receptacle 14 to atmosphere, air exhausts from the receptacle and fluid bearing a heavy load of the material rushes in through pipe 15 until there is a balancing of fluid heads within and outside the receptacle. It is an important characteristic of the described structure and operation that solid material constitutes a major part of the semi-fluid which enters the receptacle 14. This probably is due in part to the preliminary agitation of the material, and in part to the

principle of operation whereby entrance must be through a passage whose opening is embedded in the solid material and which sinks lower and lower as flow into the receptacle progresses. In any 5 event, experience has demonstrated that the receptacle will take in more of solid matter than fluid. And if a larger load is desired than what enters as above described, such as where the water head is insufficient to cause sufficient flow, suction 10 through conduit 28 may be employed to complete the loading.

Then, by closing valve 30 so that the interior of the receptacle is again closed to atmosphere, the receptacle may be elevated while atmospheric pressure holds back the contents against dropping 15 out by gravity. However, as a precaution against accidental dropping of contents, I provide for the formation under hood 17 of a fluid seal 35 which effectively restrains outflow until the valve 30 is again opened when the receptacle arrives at the 20 place of delivery, which conveniently may be into a truck or the like. As soon as the valve 30 opens the receptacle to atmosphere, weight of the contents causes outflow by gravity.

Sometimes solid matter in the receptacle 14 may become so solidly packed that it will not discharge as above described. In such a case it may be agitated by introduction of a blast of air through the conduit 21 which has a pipe extension leading well 25 down toward the bottom of the receptacle. Such an agitation disperses the massed material to an extent whereby it can discharge quickly and completely.

Figure 2 illustrates diagrammatically a case 30 where the water head is inadequate to cause a sufficient charge to enter the receptacle 14. Here suction through conduit 30 would be needed to complete the loading.

In Figure 3 there is diagrammatically represented an assembly employed for removing sludge 35 from a sewage catch basin. Little water ordinarily is available in such cases, and suction must be relied upon entirely for loading the receptacle 14a. Air pressure may be employed to force 40 the contents out of the receptacle. A two-way flap type of valve 29, as seen in Fig. 6, in such case, may serve the purpose of the water seal above 45 described.

The receptacle of Figure 5 operates similar to 50 receptacle 14 but has provision for an annular water seal 31, and has two air pressure pipes 33, 33 for agitation of contents of the receptacle.

All forms of the invention involve the principle 55 of inflow and outflow through a single, short large-diameter passage located at the bottom of the receptacle where gravity can accomplish or assist the discharge of contents. This is in decided contrast to methods involving a pumping of contents through a relatively small conduit for discharge, which conduit is subject to clogging and excessive wear.

The invention can perform effectively many 60 laborious and disagreeable tasks which hitherto have had to be performed inefficiently by manual labor, or unsatisfactorily by devices unsuited for the purpose.

Semi-fluids, as herein used, is intended to 65 embrace all mixtures wherein solid matter of any description is associated with a fluid, even though

the dispersal or dissemination of the solid matter in the fluid be merely a temporary condition resulting from agitation of the solid matter.

I claim as my invention:

1. Apparatus for evacuation of solid materials 5 which, in association with a fluid, can be made to flow, comprising a fluid-tight receptacle having a bottom inlet and discharge opening; a flexible conduit leading out of the receptacle at an upper location; a valve for said conduit whereby the 10 interior of the receptacle may be opened or closed to atmosphere at will; a hood interiorly of the receptacle and arranged across said opening, in spaced relation thereto and adapted for liquid contents of the receptacle to accumulate thereunder to provide, in conjunction with atmospheric pressure at said opening, a liquid seal against outflow from the receptacle so long as said valve is closed.

2. Apparatus for evacuation of solid materials 20 which, in association with a fluid, can be made to flow, comprising a hoist; a fluid-tight receptacle, having a bottom inlet and discharge opening, suspended on said hoist; a vacuum tank; a pressure tank; a conduit connecting 25 the vacuum tank with the interior of said receptacle through its top; a valve for said conduit adapted to open or close the interior of the receptacle to atmosphere and, in another position, to said interior to suction from the 30 vacuum tank; and a conduit leading from the pressure tank and having its end positioned for discharge well down toward the bottom of the interior of said receptacle.

3. Apparatus for evacuation of solid materials 35 which, in association with a fluid, can be made to flow, comprising a hoist; a fluid-tight receptacle having a bottom inlet and discharge opening suspended on said hoist; a vacuum tank, a pressure tank; a conduit connecting the vacuum 40 tank with the interior of said receptacle through its top; a valve for said conduit adapted to open or close the interior of the receptacle to atmosphere and, in another position, to said interior to suction from the vacuum tank; a conduit leading from the pressure tank and having its end positioned well down toward the bottom 45 of the interior of said receptacle; a valve for controlling the latter said conduit; a second conduit leading from the pressure tank having a rigid end portion adapted to be forced into material to be evacuated for agitation of said material by injection thereinto of a blast of air; and a valve for controlling this latter said conduit.

4. In apparatus for evacuation of solid materials which, in association with a fluid, can be made to flow, the combination with a receptacle having a bottom opening for inflow and for outflow of said materials, of a double acting valve for said opening, comprising a closure set across the opening and mounted and adapted to yield in inward direction under press of incoming material, and to yield in outward direction under press of discharging material; the said yielding of the closure in one direction being a swinging 60 motion which may clear said passage.

TIMOTHY F. CALLAHAN.
